Harold Beard

UNITED STATES PATENT OFFICE.

HAROLD BEARD, OF SOUTH PORTLAND, MAINE.

ADAPTER FOR RADIATOR AIR VALVES.

Application filed March 7, 1927. Serial No. 173,446.

My invention relates, in general terms, to radiator air valves.

The primary object of my invention is to provide an attachment, or adapter as I term it, which can be conveniently placed on any of the conventional type radiator air valves now generally used on radiators and which may serve, in connection with the thermostatic control largely employed in these valves, to seal the radiator against admittance of air thereto when the pressure therein is about to reduce to that below the atmosphere.

Specifically, the object of my invention is to provide means to retain the vapor, in which there still remains a considerable amount of heat, within the radiator after the boiler or gauge pressure has become negligible.

And another object sought, whereby I may accomplish this thing, is to provide an improved vacuum valve as an element in my adapter.

I have illustrated my invention in the accompanying drawing in which,—

Fig. 1 is an elevation of an ordinary radiator air valve with a sectional view of my adapter in its simplest form;

Fig. 2 is a fragmentary elevation of a radiator air valve with my adapter of preferred form shown in section;

Fig. 3 and Fig. 6 illustrate different positions of the parts when the device is operating under differing conditions;

Fig. 4 is a plan view of the vacuum valve seat, and

Fig. 5 is an inverted plan of the vacuum disc valve.

Like parts are represented by similar characters of reference throughout all the different views of the drawing.

Referring to Fig. 1, 1 represents an ordinary radiator air valve having a threaded nipple 2 for the purpose of attaching to a radiator. In order to comprehensively connect the operation of my adapter with that of the air valve certain features pertaining to the construction and actuation of these valves will be explained.

In the several views the upper end of the air valve casing is broken away, disclosing the end of the thermostatically controlled valve spindle 3 which is subject to vertical movement within the casing. The upward movement of this spindle begins shortly after the cold air has been expelled from the

casing of the valve by the on-coming steam and the latter acts on the thermostat to automatically raise the spindle and prevent further egress of steam from the radiator. 60

Upon the steam pressure in the heating system reducing to below that of the atmosphere the consequent cooling of the thermostatic device (not shown in the drawing) will allow the air valve spindle 3 to fall from 65 its seat, permitting air from the outside to enter the radiator, through the air valve, with the result that a rapid cooling of the radiator takes place.

The action just described applies to the 70 operation of the air valve when used alone, or without my adapter installed thereon.

In Fig. 1 I show a simple form of my vacuum valve adapter designed for use in connection with any thermo-operated radiator air valve and by which it is possible to prevent air entering the radiator when the pressure therein has fallen to below that of the atmosphere. 75

4 is an inverted cup-shaped member, the 80 head 4' having a venting hole 5 therein. The cylindrical portion is made to fit tightly over the body portion 1' of the air valve casing. Forced into the upper end of the cylinder 4 is a flanged disc 6, having therein 85 a hole 6' and on its upper side a raised ring portion 7 extending concentrically around the disc,—this ring constituting a valve seat upon which the thin disc 8 lightly rests and serves as a vacuum valve. 90

In Figs. 2, 3 and 6 I illustrate a preferable form of adapter and vacuum valve.

As the device is intended for use as an attachment for radiator valves already installed, and as the bodies of the valves are liable to vary somewhat in diameter, I provide considerable clearance between the walls of the adapter and the casing and insert within the recesses 9 any proper resilient packing element 10. This makes allowance 95 for varying sizes of radiator valve casings, and insures an air tight joint between the parts. 100

The body of the adapter 4 may be made as an open-ended cylinder, as shown, with 105 the flanged disc 6 forced into the upper end with a press fit so as to be air tight. This disc, 6, has on its upper side two raised portions 11 disposed concentrically with the outside circumference of the disc and each 110 other,—these raised portions forming together a channel or groove 12 within which

operates the cylindrical portion 13 depending from the valve disc 8,—the latter resting lightly on the tops of the portions 11 which act as valve seats.

5 Detachably fitting the top of the body 4 is a cover 14 having therein a vent hole 15.

In operation, the pressure of steam from the boiler first clears the radiator valve 1 of air, which, together with a certain quantity 10 of steam and vapor escapes through the vent 15, the disc valve 8 lifting slightly to allow of this,—as shown in Fig. 3. Just subsequent to the entrance of steam into the radiator valve 1, the spindle 3 through the action 15 of the thermo device will rise and close the orifice 1", preventing further egress of steam from the valve 1. It will remain closed so long as the radiator valve is hot, but immediately upon the boiler pressure 20 dropping so as to sufficiently cool the valve 1, the spindle 3 will fall from its seat in the orifice 1".

It is at this point that the vacuum valve functions, for the lowering boiler pressure 25 will soon cause a partial vacuum to form in the heating lines and radiators, and the vacuum valve 8 will seat, preventing entrance of air into the system which would cause the vacuum to be broken. Thus held 30 in the radiators, the vapor will continue to give off heat until it is itself condensed, forming a more complete vacuum which draws further steam or vapor from the boiler.

35 In the form of seat as shown in Fig. 1 it is obvious that a superior degree of excellence in the workmanship of the parts must be maintained to insure a tight fitting valve and one which will prevent the suction of air therethrough.

In Figs. 2, 3 and 6 I illustrate a type or 40 design of valve which eliminates this trouble. As previously stated, when the boiler pressure is raised and air is expelled out of the radiator valve, steam and sometimes water is forced out also. The steam within the upper portion of the valve chamber 45 will condense after the spindle valve 1 closes and provide more water to fill the groove 12, or at least cover the bottom of the depending portion 13 within the groove, making a water seal which act similarly to a trap, preventing air from passing by.

It is to be understood, of course, that this

water seal provides an additional means to 55 secure an air tight seal,—the valve 8 on the seats 11 serving as the first line in procuring this result, and the water seal supplementing the metallic seating of the parts to complete the operation of blocking all ingress of air 60 to the heating system.

Countless numbers of the plain radiator valves 1 are in operation, causing great loss to the user by reason of the heat units wasted. My adapter and vacuum valve unit 65 equipment would make of each of these valves an efficient radiator device.

Having thus described my invention, what I claim is:

1. An adapter for a radiator air valve, 70 comprising a cylindrical body member adapted to inclose the outer casing of said radiator air valve, a flanged disc fixed in said body member and having an aperture therein, upstanding projections concentrically and continuously arranged on the upper side of said disc, said projections forming an annular space therebetween, a second disc adapted to lie loosely on said projections, and a cylindrical portion extending 75 downwardly from said second named disc into said annular space, the bottom of said cylindrical portion being always in spaced relation to the bottom of said annular space.

2. An adapter for a radiator air valve, 80 comprising a cylindrical body member adapted to inclose the upper portion of said radiator valve casing, means whereby a yielding and air-tight connection between said cylindrical member and said radiator 85 valve casing may be had, a disc fixed in the upper end of said cylindrical body member having an aperture therein, upstanding projections concentrically and continuously disposed on the upper side of said disc, said 90 projections embracing an annular space, a second disc adapted to lie loosely on said projections, and a cylindrical portion extending downwardly from said second named disc into said annular space.

3. An adapter for a radiator air valve 95 having characteristics embodied in claim 2, and in addition, comprising a cover adapted to inclose the upper end of said cylindrical body member and having, therein, an aperture.

HAROLD BEARD.
